UNITED STATES PATENT OFFICE.

MARY E. TILLINGHAST, OF WEST ORANGE, NEW JERSEY.

NEEDLE-WOVEN TAPESTRY.

SPECIFICATION forming part of Letters Patent No. 268,149, dated November 28, 1882.

Application filed July 19, 1881. (Model.)

To all whom it may concern:

Be it known that I, MARY E. TILLINGHAST, of West Orange, in the county of Essex and State of New Jersey, have invented a new article of manufacture of artistic character, which 5 may be termed "Needle-Woven Tapestry;" and I hereby declare that the following is a full, clear, and exact description thereof, reference being had to the drawings which accompany 10 and form a part of this specification.

In the drawings, Figure 1 is a detail view of one example of the fabric which constitutes the groundwork of my new manufacture, on an enlarged scale. Fig. 2 is another detail 15 view, on a still larger scale, showing the method of using the needle. Fig. 3 is a view of a sample of tapestry when finished according to my invention. Fig. 4 is a side view of the fabric in the direction indicated by the arrows in 20 Fig. 2, but on a still larger scale, showing one of the embroidery-threads in position.

The nature of this invention consists in weaving with a needle a pictured design into a suitable fabric by means of various-colored silks 25 or threads in such a manner that the design, when finished, shall present the appearance of being a part of the original fabric.

To make this tapestry it is first necessary that a suitable material to serve as a background or groundwork for the design should 30 be prepared. This may be done, especially in double and triple ply goods, by causing the proposed fabric to be woven with spaces equal to about the width or thickness of one, or in 35 some instances more than one, of the woof-threads left between every two or other practicable number of the woof-threads of the material, thus constituting what is sometimes termed a "loose-weave;" or in the case of fabrics which may be woven without the requisite 40 spaces between the woof-threads—as, for example, single-ply material—such space may be obtained by drawing alternate woof-threads out of the fabric by hand. The material being 45 thus prepared, and the design to be woven in being ready, the artist or worker with a needle copies or reproduces the design by running in the different-colored silks or threads in any desired artistic combination into such 50 of the spaces left between the woof-threads as may be desired or necessary. The manner in which this is done is clearly shown in Fig. 2, in which the needle is represented at *a* as in the act of being drawn into and through the

spaces of the woof, the threads of the latter being seen at *1 1 1*, and the effect produced by the colored or ornamental threads, when drawn in, being shown at *b b* in the same figure. As shown in the figure, these ornamental threads are held in place by being passed under the warp-threads where the latter appear on the surface between the woof-threads. It is, however, proper to say that it is not essential that they should pass under every warp-thread. The number of consecutive warp-threads under 55 which they shall pass is dependent upon the length of the stitches to be made with the ornamental threads, and whether these stitches shall be longer or shorter is governed by the artistic requirements of the design to be reproduced. The work, when finished in this manner, will be found to be very effective, and for purposes of decoration or for any artistic use it presents an extremely rich appearance and is of great value. It differs materially 60 from all other decorative work done with the needle in the fact that it causes the design to seem part of the material of the background, the reason of this result being in great measure that by my method the threads which 65 form the picture can be made substantially 70 "flush" with the surface of the material, and when each of the silks or threads which are run in are—as I always prefer they should be—composed of several separate threads or filaments of different colors or of different shades 75 of the same color, part of which should harmonize with the background, the picture becomes 80 virtually a portion of the original fabric.

Having thus described my invention, what I 85 claim as new, and desire to secure by Letters Patent, is—

The new article of manufacture consisting of a needle-woven tapestry in which a pictured design is formed by the combination, with a fabric or background having spaces between its woof-threads, of colored or ornamental threads woven or filed only into these spaces and secured therein by being passed under one or more of the warp-threads lying between the woof-threads, so that the design will appear as part of the original fabric, substantially 95 as described.

MARY E. TILLINGHAST.
